FIG. 1

FIG. 2

FIG. 3

FIG. 4

FIG. 5

FIG. 1 is a perspective view of an aquarium fish net frame showing my new design; a fish net shown thereon, in broken lines for illustrative purposes;

FIG. 2 is a top plan view thereof, the bottom plan being identical to the view shown;

FIG. 3 is a side edge view thereof, the opposite side edge being identical to the side edge shown;

FIG. 4 is a rear end view thereof; and

FIG. 5 is a front end view.

The dominant features of my design reside in the full line illustration.

I claim:

The ornamental design for an aquarium fish net frame, as shown and described.
